US0D1112401S

(12) **United States Design Patent** (10) Patent No.: **US D1,112,401 S**
(45) Date of Patent: ** Feb. 10, 2026

(54) **MASON JAR SEALER**

(71) Applicant: **E. MISHAN & SONS, INC.**, New York, NY (US)

(72) Inventor: **Mohan Rajasekaran**, Watertown, CT (US)

(73) Assignee: **E. MISHAN & SONS, INC.**, New York, NY (US)

(**) Term: **15 Years**

(21) Appl. No.: **29/958,876**

(22) Filed: **Aug. 22, 2024**

(51) LOC (15) Cl. **15-10**

(52) U.S. Cl.

USPC **D15/146**

(57) **CLAIM**

The ornamental design for a mason jar sealer as shown and described.

DESCRIPTION

FIG. 1 is a top, front left perspective view of the mason jar sealer showing my design;

FIG. 2 is a left view thereof;

FIG. 3 is a right view thereof;

FIG. 4 is a front view thereof;

FIG. 5 is a back view thereof;

FIG. 6 is a top plan view thereof; and,

FIG. 7 is a bottom plan view thereof.

The broken dash-dot lines represent portions of the mason jar sealer that form no part of the claimed design.

1 Claim, 7 Drawing Sheets
